US00D555140S

(12) **United States Design Patent** (10) **Patent No.:** **US D555,140 S**
Kim et al. (45) **Date of Patent:** **** Nov. 13, 2007**

(54) **MOBILE PHONE**

(75) Inventors: **Yun-Su Kim**, Seoul (KR); **Min-Hyouk Lee**, Seoul (KR); **Jung-Hyeok Im**, Seongnam-si (KR); **Chang-Hwan Hwang**, Goyang-si (KR)

(73) Assignee: **Samsung Electronics Co., Ltd.**, Suwon-Si (KR)

(**) Term: **14 Years**

(21) Appl. No.: **29/263,630**

(22) Filed: **Jul. 27, 2006**

(30) **Foreign Application Priority Data**

May 11, 2006 (KR) 30-2006-0017476

(51) **LOC (8) Cl.** **14-03**

(52) **U.S. Cl.** **D14/138**

(58) **Field of Classification Search** D14/137-138, D14/147-148, 156, 218, 247-248, 341-347, D14/496; D16/208, D21/329, 331, 333, D21/517; 348/14.01-14.02; 361/814; 379/433.01-433.13; 455/556.1-556.2, 575.1, 455/575.3, 575.4, 566, 90.3
